UNITED STATES PATENT OFFICE.

CHARLES L. ROWLAND, OF CARBONDALE, PENNSYLVANIA, ASSIGNOR TO AMERICAN WELDING COMPANY, OF CARBONDALE, PENNSYLVANIA, A CORPORATION OF PENNSYLVANIA.

METHOD OF MAKING METAL CONTAINERS.

1,216,733.

Specification of Letters Patent. Patented Feb. 20, 1917.

Application filed May 11, 1915. Serial No. 27,401.

To all whom it may concern:

Be it known that I, CHARLES L. ROWLAND, a citizen of the United States, residing in Carbondale, county of Lackawanna, State of Pennsylvania, have invented certain new and useful Improvements in Methods of Making Metal Containers, of which the following is a specification.

This invention contemplates the production of a container, constructed of metal, comprising a body, usually cylindrical, with closed end heads, the parts or sections of the container being integrally united by welding.

15 In the accompanying drawings, Figures 1 to 14 show progressively the construction of the container and the contours which may be given it.

20 Fig. 1 shows a flat plate of rolled metal: Fig. 2 shows this plate rolled into approximately cylindrical form with its edges overlapped to be welded together as at *a*:

Fig. 3 shows the complete, welded cylindrical body so produced:

25 Fig. 4 is a side view of one of the heads *b*, partly in section:

Fig. 5, a face view of the same:

Fig. 6, a side view of the other head *c*, also partly in section:

30 Fig. 7, a face view of same:

Figs. 8 and 9 show the flanged heads *b* and *c* inserted in the ends of the cylinder.

Where the flanges of the head overlap the side portions of the cylinder, the parts are 35 united by a welding operation produced in stages, that is a section of the joint is adequately heated and welded and then another section is similarly treated, and so on throughout the whole of the seam. By this 40 method large and perfect containers may be produced, which is not feasible under the method practised in the making of comparatively small containers; which method consists in heating, in a suitable furnace, at 45 one time the whole of the joint and then welding the same by a rolling method. The longitudinal weld in the body of the cylinder above referred to may be effected by a similar stage welding method. A suitable way 50 of accomplishing this is to heat the metal progressively along the line of the weld by traveling furnaces and then effecting the welding by pressure rolls or impact devices.

Figs. 10 and 11 illustrate crimping the

55 united welded parts of the flanges of the heads and adjacent portions of the ends of the cylinder. In Fig. 10, the inserted head *b* is concave considering the exterior; and its flange and the part of the cylinder to which it is welded are together crimped 60 transversely to the axis of the cylinder or body and, as shown, inwardly toward the center thereof. Fig. 11 shows the same general arrangement, the only difference being that the central part of the cylinder head *c* 65 is flat in a plane at right angles to the axis of the body.

Fig. 12 shows the same general arrangement as Fig. 11 except that the body of the flanged head *c* is forced outwardly so that in 70 cross-section the body of the head is concavo-convex. Such outward concavo-convex formation of this head, and the other head also if originally flat, may be produced by internal pressure. The fluid pressure 75 medium may be admitted through a tapped orifice *x* in the wall of the body adjacent one of the heads. This may be readily accomplished because the testing pressure may be carried very materially higher than the 80 pressure of the fluid to be stored or transported in the container and there is, therefore, no distortion of the head after its initial projection has been effected by the testing pressure. The crimped welded 85 flanged portions of the heads and contiguous end portions of the body not only add strength to the structure but the projecting crimped portion or chime of the structure affords an end depression that serves to prevent shocks therewith. The containers contemplated by this invention are preferably 90 made of steel which not only affords the desired strength but also lends itself peculiarly well to the integral uniting of parts to be 95 attached by a welding operation. The class of containers that I have particularly in mind are for chemicals and are well adapted for the transportation and storage of 95 chlorin.

100 Of course, the outward swelling of the head *c* when it is in position and has been welded to produce in its body the concavo-convex shape in cross-section, as already referred to, may not be necessary for most 105 purposes.

Now referring to Figs. 13 and 14 the crimped chime portion, marked in Fig. 13

2
 d, provides at the end of the container a depression affording protection for the closures f, f' of pipes g, g' that extend radially from the central part of the head to 5 points adjacent the body of the container and that may or may not be curved to conform to the concavo-convex head; these pipes g, g' are preferably diametrically opposite, as indicated in Fig. 14. Therefore, 10 by placing the container in such position that the pipes g, g' occupy a position vertically in line, or substantially so, I may withdraw through the upper pipe g' (Fig. 13) any gaseous matter from within the container first, and may then withdraw through 15 the lower pipe g any liquid matter. When the pressure of the contained gas is designed to effect the evacuation of the liquid, the tap f is first utilized.

20 When the central portion of the head or heads is expanded or forced outwardly, as described, such special expansion may be performed either before or after the crimping of the weld-united portions of the 25 flanges and end parts of the body or cylinder, the sequence of these two operations being not of the essence of claims herein. However, I prefer that the crimping or inward turning of the chime-like portions of 30 the vessel should be first completed and afterward the expansion of the heads be effected by internal pressure.

It has heretofore been the practice of securing the filling and discharging pipes of 35 containers of this character to a man-hole plate, which in turn is secured to one of the heads, generally by bolts and made tight by gaskets. Such an arrangement is in many cases unsuitable for containers intended 40 to hold chemicals of various kinds. By the method of this invention the containers are perfectly tight, all parts, by the welding process, being integral. The pipes g, g' may be attached to the head before the head 45 is welded in the body; or the head to which the pipes are to be attached is first secured in place, the pipes then attached thereto and the other head finally welded in the body to complete the container.

50 Of course, both heads may be initially flat and be expanded into concavo-convex form by pressure applied to the interior of the container.

I claim:

55 1. The method of making a metal container, which consists in first forming a cylindrical body, then inserting within the body a flanged head, then integrally welding in stages the flange of the head with

the adjacent end of the cylindrical body, 60 and then crimping the parts so welded.

2. The method of making a metal container, which consists in first forming a cylindrical body, then inserting within the body a flanged head, then integrally welding in stages the flange of the head with the adjacent end of the cylindrical body, and then bending the head into a concavo convex form. 65

3. The method of making a metal container, which consists in first forming a cylindrical body, then inserting within the body a flanged head, then integrally welding in stages the flange of the head with the adjacent end of the cylindrical body, 75 then crimping the parts so welded, and then bending the body of the head into a concavo convex form.

4. The method of making a metal container, which consists in first forming a cylindrical body, then inserting within the body at each end a flanged head, then integrally welding in stages the flanges of the head with the adjacent ends of the cylindrical body, and then forcing the heads outward by internal pressure. 85

5. The method of making a metal container, consisting in first forming a cylindrical body, then inserting within the body flanged heads, the flanges of which extend 90 outwardly and laterally from the body of the heads, integrally connecting the body and heads by welding in stages the adjacent parts of the body and flanges of the heads and in attaching to the inside of one of the 95 heads filling and discharge pipes before both of the heads are welded to the body.

6. The method of making a metal container having filling and discharge pipes, which consists in integrally welding to a 100 cylindrical body a head at each end and in attaching to the inside of one of the heads filling and discharge pipes before both of the heads are welded to the body.

7. The method of making a metal container having filling and discharge pipes, which consists in integrally welding to one end of the cylindrical body a cylinder head, then connecting to said head filling and discharge pipes and then integrally welding 110 to the opposite end of the cylindrical body a cylinder head.

In testimony whereof, I have hereunto subscribed my name.

CHAS. L. ROWLAND.
